UNITED STATES PATENT OFFICE.

ROBERT B. SWANN, OF VERNON, TEXAS.

HAME-HOOK:

SPECIFICATION forming part of Letters Patent No. 513,217, dated January 23, 1894.

Application filed December 6, 1892. Serial No. 454,312. (No model.)

To all whom it may concern:

Be it known that I, ROBERT B. SWANN, a citizen of the United States, and a resident of Vernon, county of Wilbarger, State of Texas, have invented certain new and useful Improvements in Hame-Hooks, of which the following is a full, clear, and exact description, reference being had to the accompanying drawings, forming a part hereof.

10 My invention relates to improvements in hame-hooks, the objects in view being the production of a hame-hook that may be readily applied to the hames or removed therefrom, and which while in position is secure against any accidental loosening or removal; and furthermore, is strong, cheap, and durable.

With these and other objects in view the invention consists in certain features of construction hereinafter specified and particularly pointed out in the claims.

20 Referring to the drawings:—Figure 1 is a perspective view of a portion of a hame-section, the same being provided with a hook constructed in accordance with my invention. Fig. 2 is a detail in perspective of the hook, the reverse side being shown to that shown in Fig. 1. Fig. 3 is a horizontal sectional view through the hame-section and hook. Fig. 4 is a detail in perspective of the locking-key.

Like numerals of reference indicate like parts in all the figures of the drawings.

The hook 1 has the usual external shape, in that it consists in a bent arm or hook-portion 2, and has formed at its rear or inner end the elongated cylindrical eye 3. This eye is provided at one side with an opening 4, longitudinally disposed, and forming an entrance to the longitudinal bore 5 formed throughout the cylindrical eye 3. This bore 5 has formed at its outer side a V-shaped groove 6, which forms a continuation of the bore or rather forms one wall thereof.

45 The hame-section 7 is of the usual construction and is provided with the ordinary staple 8.

In order to apply the hook to the staple it is simply necessary to pass the eye laterally over the staple, the slot or opening 4 forming

ing a passageway for the staple, and after 50 the insertion or application of the hook to the staple a key 9 is inserted into the V-shaped groove, completely filling the same and that part of the bore which is not occupied by the staple.

55 The key 9 is somewhat triangular in cross-section and is provided with a concavity 10 which corresponds to the curvature of the bore in cross-section, and therefore snugly embraces that portion of the staple not embraced by the bore. The key is secured in position in any suitable manner, but preferably through the medium of a pin or binding-screw 11, which is passed laterally through a perforation 12 formed in the eye 3 and communicating with the groove 6 formed at the side of the bore.

60 It will be seen that at any time the hook may be removed by simply withdrawing the pin or binding-screw 11 from the perforation and the key from its position or seat. This admits of a lateral movement of the hook, so that the passageway or slot 4 may be brought opposite the vertical portion of the staple and the eye withdrawn from over 65 the same.

I construct the hook in practice somewhat heavier than the ordinary hook in order to lend additional strength, and it will be seen that the eye forms a broad bearing-portion 80 upon which the usual wear will have but little effect.

70 From the foregoing description in connection with the accompanying drawings it will be seen that I have provided a cheap and 85 simple construction of hook, the same being durable and readily applied to any of the ordinary hame-sections now in use, and when so applied is secure and reliable.

Having described my invention, what I 90 claim is—

1. The herein described hame-hook having an elongated open eye at an angle thereto adapted to loosely engage a staple, and a removable key adapted to be fitted in the eye 95 and to clamp upon said staple, and means for securing the key in position, substantially as specified.

2. The herein described hame - hook, the same consisting of the hook portion 2, the eye 3 having a bore throughout its length and at one side of which there is formed the V-shaped key-seat 6, and the slot 4 at the side of the bore and communicating therewith, and the substantially triangular key 9 the inner face of which is concaved to agree with

the curvature in cross-section of the bore, substantially as specified.

In testimony whereof I affix my signature in the presence of two witnesses.

ROBERT B. SWANN.
